UNITED STATES PATENT OFFICE.

HENRY F. JOECKEL, OF CAMP POINT, ILLINOIS.

TWO-PARTY TELEPHONE SYSTEM.

1,111,024.

Specification of Letters Patent. Patented Sept. 22, 1914.

Application filed February 15, 1912. Serial No. 677,668.

To all whom it may concern:

Be it known that I, HENRY F. JOECKEL, a citizen of the United States, residing at Camp Point, in the county of Adams and State of Illinois, have invented new and useful Improvements in Two-Party Telephone Systems, of which the following is a specification, and which is illustrated in the accompanying drawing.

10 The invention relates to two-party selective signaling systems in which two line wires are used with annunciators of substations connected to ground from each line wire.

15 The object of this system is to provide means by which two parties of a telephone line may selectively signal one another or the central station and in which the central station can selectively signal the parties.

20 These objects are obtained in the mechanism and system of wiring, as hereinafter described and shown in the accompanying drawing.

The drawing represents a central station 25 at 20, and substations at 21, and 22, of a two party selective signaling telephone line. The line wires are shown at L¹, and L², and at 14 the annunciator of the central station which is bridged from L¹, to L², at the line 30 jack 13, by contacts c, and d, at the line jack springs a, and b, respectively. The annunciator 14, is cut out as usual whenever a switching plug is inserted into the line jack. At L³, and L⁴, a portion of the leads of a 35 cord set terminating in a switching plug is shown. The magneto 1, is connected to ground on one side and is connected on the other side to a switching lever P by which the magneto may be connected to L³, or L⁴, 40 which register with L¹ and L² respectively, whenever the switching plug is inserted into the line jack.

In the drawing like numbers represent like parts.

45 The telephones of substations 21 and 22 each have a magneto 1, an annunciator 2, transmitter 3, receiver 4, induction coil 5, local battery 6, switch hook 7, condenser 8, and a switch F, and station 21 has a switch 50 E, these switches F, and E, may be of the ordinary push-button type.

The telephone of substation 21 has binding posts A, B and C, and is connected to L¹ by binding post C, to L² by binding post 55 A, and to the ground by binding post B. The secondary talking circuit from L² to L¹

is by binding post A, wire f', switch hook 7, wire f", induction coil 5, wire f", condenser 8, receiver 4, wire f, and binding post C; the circuit is however normally interrupted at the switch hook. The normal circuit of 60 the annunciator is from L² to ground, by binding post A, wire f', contact k, switch-arm F, wire h', annunciator 2, wire h, switch-arm E, contact and wire f", and binding post B. The magneto 1, has two circuits which are used in this system one is from L¹ to L², by binding post C, wire f, contact o, switch-arm E, wire h", automatic 65 cut out s, magneto 1, switch-arm F, contact k, wire f', and binding post A, the other circuit is from L¹ to ground, by binding post C, wire f, contact t, switch-arm F, magneto 1, automatic cut out s, wire h", switch-arm E, contact and wire f", and binding post 70 B. This telephone set is wired in accordance with the telephone system of Patent No. 1,007,575.

The telephone of substation 22 has binding posts A', B', and C', and is connected to L¹, by binding post C', to L² by binding post A', and to the ground by binding post B'. The secondary talking circuit from L¹ to L² is by binding post C', wire f, receiver 4, condenser 8, wire f", induction coil 5, wire f", switch hook 7, wire f', and binding post A'; the circuit is however normally interrupted at the switch hook. The normal circuit of the annunciator is from L¹, to ground, by binding post C', wire f, contact k, switch-arm F, wire h", automatic cut out q, wire h', 85 annunciator 2, wire h, wire f", and binding post B'. The magneto 1, has two circuits one is from L² to L¹, by binding post A', wire f', wire r, magneto 1, automatic cut out s, wire h", switch-arm F, contact k, wire f, and binding post C', the other circuit is from L² to ground by binding post A', wire f', wire r, magneto 1, automatic cut out s, wire h", switch-arm F, contact t, wire f", 90 95 and binding post B'. In this telephone system the annunciator at a station must first be disconnected from its normal circuit before that station can selectively signal another station this may be accomplished several ways at a substation therefore I have shown two different styles of wiring, either or both styles may be used upon a line.

I recommend the bells and magnetos of the usual bridging telephone system to be 110 used in this telephone system, it however is to be understood that other styles of an-

nunciators and magnetos may be used in this system, the annunciators must however be adapted to operate with the current of the magneto of the station calling or the magneto or generator must produce a current suitable to operate the annunciator of the station called.

The construction and operations of the parts used in the combination of this two-party telephone system are so well known that no further explanation will be needed.

What I do claim as my invention, and desire to secure by Letters Patent, is—

1. The combination, in a two-party local battery magneto telephone system, a central station, a metallic circuit leading therefrom normally closed at said station by an annunciator, two substation talking sets bridged into the said metallic circuit; said bridges being however normally interrupted at the switch hook, an annunciator at each of said substations normally connected to ground one from one side of the metallic circuit the other from the other side of the metallic circuit, a magneto in normally open circuit at each substation and means at each substation to disconnect the annunciator from its normal circuit and at the same time to place the magneto selectively in circuit with the annunciator of the other substation or in circuit with the annunciator of the central station, and means at the central station to

selectively signal either substation upon their respective sides, substantially as described.

2. The combination, in a two-party local battery magneto telephone system, a central station, a metallic circuit leading therefrom normally closed at said station by an annunciator, two substation talking sets bridged into the said metallic circuit; said bridges being however normally interrupted at the switch hook, an annunciator at each of said substations normally connected to ground one from one side of the metallic circuit the other from the other side of the metallic circuit, a magneto in normally open circuit at each substation and means at each substation to cut the annunciator out of circuit at the substation and to place the magneto at the same selectively in circuit with the annunciator of the other substation or in circuit with the annunciator of the central station, and means at the central station to selectively signal either substation upon their respective sides, substantially as described.

In testimony whereof I have signed my name to this specification in the presence of two subscribing witnesses.

HENRY F. JOECKEL.
